UNITED STATES PATENT OFFICE.

JACOB N. KEEFER AND WILLIAM A. REYNOLDS, OF WARRENSBURG, ILL.

COFFIN.

SPECIFICATION forming part of Letters Patent No. 233,356, dated October 19, 1880.

Application filed June 2, 1879.

To all whom it may concern:

Be it known that we, JACOB N. KEEFER and WILLIAM A. REYNOLDS, both residents of the town of Warrensburg, county of Ma- 5 con, and State of Illinois, have invented cer- tain new and useful Improvements in Coffins, of which the following is a specification.

Our invention relates to coffins, and is de- 10 signed, first, to furnish a safe and superior means by which coffins may be lowered into graves, and, second, to act as fastenings for the lids.

The device consists in a set of rods or bands 15 extending along the inside surface of the coffin, securely attached to the bottom, and pro- vided with ornamental knobs or projections above the surface of the coffin, said knobs each constructed with a horizontal slot of suit- 20 able dimensions to admit the strap or band generally used to lower coffins, and provided with threads which screw onto the ends of the rods in the manner of thumb-nuts.

In the drawings accompanying and forming 25 a part of this specification, Figure 1 is a ver- tical section of the head of a coffin, with de- vice shown as connected with a cross-piece or band on the lower surface of said coffin. Fig. 2 is a vertical section of the foot of a coffin, showing a single rod terminating in a strap 30 bent to conform to the inside surface of the coffin and attached by screws or other suitable means thereto, as also shown in Fig. 3. Fig. 3 is a longitudinal section of coffin and rough box, showing position of device with relation

to the ends of coffin, and also the slots in the 35 knobs. Fig. 4 shows various conformations of or substitutions for the slot in the knobs, each of which may be ornamented in a suit- able manner.

A represents the coffin; B B', the rods or 40 bands; C, the knobs, with slots c. D D are the bands or straps used for lowering pur- poses, and E shows the rough box provided with knobs attached, which knobs need not be so elaborate as those used on the coffin. 45

The device is designed to be attached in such a manner that whatever its peculiar con- struction or position on the coffin the lining will conceal it.

In the drawings the coffin shown is supposed 50 to be of medium size. In larger sizes the ar- rangement shown in Fig. 1 is used on both ends, and, if necessary, in the middle also. In small sizes the band attachment in Fig. 2 is preferred.

Having thus described our invention, we 55 claim—

The lowering device C, constructed as shown, in combination with straps D D and rods B B', all for the purpose of securing the coffin- 60 lid and lowering the coffin into graves, sub- stantially as herein set forth.

WILLIAM A. REYNOLDS.
JACOB N. KEEFER.
